Primary Examiner — Sandra Snapp(74) *Attorney, Agent, or Firm* — Schmeiser, Olsen & Watts, LLP(57) **CLAIM**

I claim the ornamental design for a modular sofa, as shown and described.

DESCRIPTION

FIG. 1 is a perspective view of a first embodiment of the present invention showing a modular sofa;

FIG. 2 is a top plan view thereof;

FIG. 3 is a left side elevation view thereof;

FIG. 4 is a right side elevation view thereof;

FIG. 5 is a rear perspective view thereof;

FIG. 6 is a bottom plan view thereof;

FIG. 7 is a perspective view of a second embodiment of the present invention showing a modular sofa;

FIG. 8 is a top plan view thereof;

FIG. 9 is a left side elevation view thereof;

FIG. 10 is a right side elevation view thereof;

FIG. 11 is a rear perspective view thereof; and,

FIG. 12 is a bottom plan view thereof.

The broken lines in the figures show unclaimed detail.
